(57) CLAIM

I claim the ornamental design for a roasting device handle, as shown and described.

DESCRIPTION

FIG. 1 shows a perspective view of a roasting device handle of the present invention;

FIG. 2 shows a left side view of the roasting device handle of FIG. 1;

FIG. 3 shows a right side view of the roasting device handle of FIG. 1;

FIG. 4 shows a rear view of the roasting device handle of FIG. 1

FIG. 5 shows a front view of the roasting device handle of FIG. 1;

FIG. 6 shows a top view of the roasting device handle of FIG. 1; and,

FIG. 7 shows a bottom view of the roasting device handle of FIG. 1.

The broken lines in the drawings represent portions of the article that form no part of the claim.

1 Claim, 3 Drawing Sheets
